UNITED STATES PATENT OFFICE.

JOHN W. STEWART, OF LAPORTE CITY, IOWA.

DRAIN-HEAD.

1,150,400.

Specification of Letters Patent. Patented Aug. 17, 1915.

Application filed July 23, 1914. Serial No. 852,652.

To all whom it may concern:

Be it known that I, JOHN W. STEWART, citizen of the United States, residing at La-
porte City, in the county of Blackhawk and
5 State of Iowa, have invented certain new
and useful Improvements in Drain-Heads,
of which the following is a specification.

This invention relates to certain new and
useful improvements in drain heads and has
10 as its principal object to provide a drain
head which may be embedded within the soil
and so constructed as to collect and direct
water percolating through the soil into the
drain.

15 The invention has as a further object to
provide a drain head including a non-porous
or impervious body portion in which is ar-
ranged a porous filler, water being adapted
to enter through the porous filler to be
20 thence collected by the non-porous body por-
tion and directed into the drain.

25 A further object of the invention is to
provide a drain head of this character
wherein the inner floor of the non-porous
body portion will be provided with chan-
nels converging toward a centrally disposed
30 water collecting chamber, and wherein said
channels will be arranged beneath the porous
filler so that water entering through said
porous filler will be collected within said
channels to be thence directed to the central
35 water collecting chamber and thence to the
drain.

40 The invention has as a further object to
provide a porous filler having interstices
ramifying in all directions so that water may
readily percolate through the filler to gain
access to the drain.

45 A still further object of the invention is
to provide a drain head wherein the base or
body portion will be so constructed as to
provide a rigid support for the porous filler,
and will be so formed as to readily direct
50 water entering through the porous filler into
the drain.

With these and other objects in view my
invention will be more fully described, illus-
trated in the accompanying drawing and
then specifically pointed out in the claim
55 which is attached to and form a part of this
application.

In the accompanying drawings:—Figure
1 is a sectional view of my improved drain
head illustrating the head embedded with-
55 in the soil and also showing the manner in
which a drain pipe is connected thereto, Fig.

2 is a top plan view of the drain head, Fig.
3 is a similar view thereof showing the
porous filler removed from the body portion
of the head, and Fig. 4 is a front elevation
60 of the drain head.

Corresponding and like parts are referred
to in the following description and indicated
in all the views of the drawings by the
same reference characters.

Referring more particularly to the draw-
ings, my improved drain head includes a
preferably octagonal body portion 10 hav-
ing a bottom wall 11 and a side wall 12.
Although I have indicated that the body
70 portion 10 is preferably octagonal, still, it
is to be understood that said body portion
may be of any desired shape or size, and the
thickness of the bottom and side walls 11
and 12 may be correspondingly varied, as
75 exigency may demand. The body portion
10 is preferably formed of solid cement rel-
atively impervious to water although any
other suitable material may be employed,
and medially formed in the bottom wall 11
80 thereof is a water collecting chamber 13, the
said chamber opening through the floor of
the body portion. Communicating with the
water collecting chamber 13 and opening
through the outer face of the bottom wall
85 11, is a suitable aperture preferably of
greater diameter than the diameter of the
water collecting chamber 13, the said aper-
ture being designed to receive one extremity
of an adjacent pipe section 14 forming the
90 drain. By this construction, it will be ob-
served that an annular shoulder is provided
at the inner extremity of the opening which
receives the extremity of the pipe section 14
against which the said pipe section may abut
95 to be thus held securely in position com-
municating with the water collecting cham-
ber 13.

100 The inner face 15 of the bottom wall 11
or the floor of the body portion is prefer-
ably concave, substantially, the said floor
sloping in all directions toward the water
collecting chamber 13 and formed in said
105 floor are a plurality of radially extending
channels 16. The channels 16 each extend
at one end from the inner face of the side
wall 12 to communicate with the water col-
lecting chamber 13 at their opposite ends
and open through the upper face of the
floor, as shown in Fig. 3 of the drawings.
110 Preferably, said channels are provided with
converging side walls, the said channels be-

ing of greater width at their outer extremities than at the point where they enter the water collecting chamber 13. In thus constructing and arranging the channels in this manner, it will be observed that said channels will effectually drain off water entering upon the floor of the body portion into the water collecting chamber 13 and in forming said channels wider at their outer extremities, than at their inner extremities, a correspondingly increased draining capacity of said channels is obtained. In other words, the said channels are made correspondingly wider as the area of the floor of the body portion increases so as to permit water to find ready access to said channels.

Disposed within the body portion 10 and resting upon the floor thereof, is a filler 17, the said filler being confined by the side wall 12 of the body portion and having its upper face preferably arranged in transverse alignment with the upper edge of said side wall. The filler 17 is porous and is preferably formed by coating particles of gravel, pebbles or other similar hard material with cement, the coated mass of such substance being then poured into the body portion and allowed to harden. In thus using a relatively coarse base for the filler 17, the pebbles or gravel forming such base, will contact and harden together at such points of contact, providing interstices within the filler ramifying in all directions. As will be clear, water will readily enter through such interstices of the filler 17, to be collected upon the floor of the body portion 10 and by the channels 16, whence it will be thence directed into the collecting chamber 13 to find exit through the drain pipe 14. If desired, the filler 17 may be provided with a plurality of vertically disposed apertures or channels 18 through which water or moisture may directly enter upon the floor of the body portion, but by constructing the filler 17 in the manner just above described, such channels 18 will not, under ordinary circumstances, be required.

It will thus be seen that the body portion 10 being preferably monolithic and being formed of hard cement, will effectually support the porous filler 17, and thus a practically integral structure is provided. In this connection, attention is directed to the fact that when the filler 17 is poured into the body portion 10, the cementitious substance with which the filler is coated, will harden at the points of contact of the filler with the body portion to thus secure the filler thereto. In Fig. 1 of the drawings, I have illustrated the drain pipe 14 connected with the drain head as constructed in accordance with the present invention. Since such drain pipe forms no part of the present invention, it has not been specifically de-

scribed. However, as a means of positively connecting the drain pipe with the drain head, the drain head may have a plurality of apertures formed therein to extend transversely through the drain head adjacent the drain pipe 14 and a wire or other suitable flexible element 19 may be threaded through said apertures and wrapped around the drain pipe. While this means of connecting the drain pipe 14 with the drain head may be employed, if desired, still, it is to be understood that it is not absolutely necessary to thus connect the drain pipe with the drain head since, under ordinary circumstances, the drain pipe will maintain its engagement with the drain head.

In view of the above description a further explanation as to the operation of my improved drain head seems hardly necessary. However, it will be stated that the drain head may be embedded within the soil as shown in Fig. 1 of the drawings, or may be otherwise arranged as found desirable, and the drain pipe is connected with the drain head as therein illustrated. Water filtering through the soil and entering upon the porous filler 17 will thence pass through the interstices in said filler to be deposited upon the floor of the body portion and within the channels 16. The floor of the body portion being concave and the bottom walls of the channels 16 being inclined inwardly toward the collecting chamber 13, the said water will be directed to said chamber to thence find exit through the drain pipe 14. 100

While I have indicated that the filler 17 is preferably formed in the manner above described, still, it will be clear that any suitable porous substance may be substituted and if desired, after the body portion 10 of the drain head has been arranged in position, as shown in Fig. 1 of the drawings, such porous substance may then be placed within the body portion in loose or natural condition. In other words, the body portion 10 of the drain head, could be filled with coarse gravel or cinders, as a substitute for the filler 17, herein described. 110

Attention is now called to the fact that while my improved drain head is particularly adapted for the purpose indicated, still, it will be seen that the said head is so constructed as to be readily adaptable for use in the diffusion of water for irrigation or other similar purposes. When thus used, water entering within the body portion 10 through the drain pipe 14 will be directed into the collecting chamber 13 when it will thence spread laterally through the channels 16 to be thence diffused over the porous filler 17. It will be observed that the said channels 16 are so disposed as to lead the water directly to diversified points of the filler 17 so that the entire filler will become thoroughly saturated. 130

It will therefore be seen that I provide a very simple and efficient construction for the purpose set forth and by such construction provide an article which may be used either as a drain head for the collection of moisture or may be used, with equal facility, as a terminal for the diffusion of moisture.

Having thus described my invention, what I claim and desire to secure by Letters Patent is:—

A device for the purposes set forth consisting of an impervious monolithic body having a bottom and an annular side wall rising from the edge of the bottom, the bottom having a central chamber opening therethrough in its upper side and an enlarged aperture in its lower side communicating directly with said chamber, the upper side of said bottom being concave and further

provided with channels radiating from the said chamber to the annular side wall and increasing in width toward their outer ends, a monolithic porous filler in the body above the bottom thereof and intimately connected to the annular side wall, said filler having channels therethrough, a pipe having its end fitted in the aperture in the bottom of the body, and a tying device inserted through the bottom of the body and through the channels in the filler to secure said pipe thereto.

In testimony whereof I affix my signature in presence of two witnesses.

JOHN W. STEWART. [L. s.]
